UNITED STATES PATENT OFFICE.

CARL DANIELSON, OF CHICAGO, ILLINOIS.

HORSESHOE.

1,311,680.

Specification of Letters Patent.

Patented July 29, 1919.

Application filed February 21, 1917. Serial No. 150,041.

To all whom it may concern:

Be it known that I, CARL DANIELSON, a citizen of the United States, residing at Chicago, in the county of Cook and State of Illinois, have invented certain new and useful Improvements in Horseshoes, of which the following is a specification.

This invention relates to improvements in horseshoes having removable calks. One object is to provide a horseshoe that may be instantly changed, without removal from the foot of the animal, to suit changes in the weather, roads, and the work to be performed. With the foregoing and other objects in view the invention consists in the combination and arrangement of parts to be hereinafter fully described, pointed out in the appended claim and illustrated in the accompanying drawing which forms a part of this specification and in which—

Figure 1 is a cross-section on line 4—4 of Fig. 2.

Fig. 2 is an inverted plan view of Fig. 1.

Fig. 3 is a view of Fig. 2 with the calks removed.

Fig. 4 is a perspective view of one form of calk employed.

Like reference characters denote corresponding parts throughout the several views. The reference numeral 1 denotes the master plate or horseshoe proper which is formed with enlarged apertured lobes 11 formed with recesses 11^a to releasably receive the oblong heads 12 of the wedge-shaped calks 13, said heads and calks being connected by stems 14, said heads being formed with apertures 14^a. The mouth 11^b of each recess in each lobe is narrower than the recess and is adapted to receive the stem portion 14 of the calk 13, the head 12 being adapted for disposal in the recess 11^a. The calk is introduced from either end of the recess 11^a and mouth 11^b. When the head is

introduced into the recess between the lobes it is retained in position by screw 15 introduced into the threaded openings 16 in said lobes, said screw also passing through the opening 14^a in the head 12 of the calk.

The screw 15 is formed with an aperture 17 adapted to receive another screw 18 which is adapted for engagement with the threaded aperture 19 in said lobe, the aperture 19 being disposed at right angles to the aperture 16. When the screws 15 and 18 are in engagement, as shown in Figs. 1 and 2, they are positively locked and they serve to lock the head 12 in fixed position within the said lobes 11. To release the calk 13 the screws 15 and 18 are manually disengaged and removed from the lobes and the head 12 and stem 14 moved out of the lobes. It is obvious that calks of various shapes and sizes may, in this manner, be readily secured to the plate or shoe and as readily removed without inconvenience to the animal.

What is claimed is:—

In a horseshoe, a master plate formed with recessed and perforated lobes, calks with heads formed thereupon for passage into and out of the recessed portions of said lobes, apertured screws adapted for insertion into perforated portions of said lobes for engagement with said calks, and screws adapted for insertion into perforated portions of said lobes and passage through the apertured portions of the first-named screws to retain the same in adjusted position with relation to the said calks.

In testimony that I claim the foregoing as my own I have hereto affixed my signature in the presence of two subscribing witnesses.

CARL DANIELSON.
